UNITED STATES PATENT OFFICE.

NELL F. WINGET, OF MINNEAPOLIS, MINNESOTA.

DESIGN FOR A CAP OR BONNET.

48,575.

Specification for Design.

Patented Feb. 15, 1916.

Application filed October 18, 1915. Serial No. 56,623. Term of patent 14 years.

To all whom it may concern:

Be it known that I, NELL F. WINGET, a citizen of the United States, residing at Minneapolis, in the county of Hennepin and State of Minnesota, have invented a new, original, and ornamental Design for a Cap or Bonnet, of which the following is a specification, reference being had to the accompanying drawings, forming part thereof.

Figure 1 is a perspective view looking at the front of the cap; and Fig. 2 is a rear elevation of the cap.

I claim:

The ornamental design for a cap or bonnet, as shown.

NELL F. WINGET.

Witnesses:

F. D. MERCHANT,

HARRY D. KILGORE.
